HYDRAULIC CUTTING TOOL

Walter E. Northcutt, Chebanse, Ill., assignor to
Manco Mfg. Co., Bradley, Ill., a corporation of
Illinois

Application November 10, 1948, Serial No. 59,363

3 Claims. (Cl. 30—92)

1

This invention relates to hydraulic cutting tools, and has to do more particularly with a cutting tool suitable for cutting wire ropes or cables and analogous articles.

Hydraulic cutting tools are known and are used for various purposes. In general, the known tools are excessively heavy and large, are cumbersome and difficult to handle, are rather expensive and have to be held in a certain manner or position in use. My invention is directed to the provision of a hydraulic cutting tool of compact construction, which will operate satisfactorily in any position, is of comparatively light weight and may be produced at comparatively low cost. It is also an object of my invention to provide a cutting tool of the character stated which is free of objectionable projections such as would interfere with use of the tool in restricted spaces. The cutting tool of my invention comprises a cylinder and a piston operating therein providing, with the cylinder, a reservoir chamber at one side of the piston, for the operating hydraulic fluid or liquid, and a pressure chamber at the other side of the piston to which the operating liquid is delivered under pressure from the reservoir chamber, for applying high pressure to the piston and thereby forcing the cutting blade of the tool in cutting direction. By having a portion of the cylinder serve as a reservoir chamber, the overall dimensions of the tool may be reduced, which is conducive to compactness of construction and reduction in size of the tool. I also provide means whereby the piston, and with it the cutting member or blade, may quickly be returned to outer or retracted position, upon completion of the cutting operation, which is desirable as increasing the cutting capacity of the tool. During the cutting operation, pressure is applied to the cutting blade by the piston rod in contact therewith, thereby reducing likelihood of breakage of parts, such as is apt to occur where the pressure is transmitted from the piston rod to the blade through a connecting pin or like member. I also provide pressure release means whereby the pressure at the high pressure side of the piston may be relieved when it reaches a predetermined high value, thus guarding against breakage or damage to the tool, such pressure relief means being carried by the piston within the cylinder so as to be guarded effectively thereby while avoiding objectionable projections beyond the cylinder. Further objects and advantages of my invention will appear from the detail description.

In the drawings:

Figures 1A and 1B taken together are a transverse axial sectional view of a hydraulic cutting tool embodying my invention, certain parts being shown in plan and the inner cylinder head and the parts carried thereby being shown in plan, the cylinder being shown fragmentarily in plan and broken away;

2

Figure 2 is an outer end view, on an enlarged scale, of the inner cylinder head and the cutter head and associated parts carried thereby;

Figure 3 is a sectional view, on an enlarged scale, taken substantially on line 3—3 of Figure 1; and

Figure 4 is a sectional view, on an enlarged scale, taken substantially on line 4—4 of Figure 1, certain parts being shown in elevation, showing a wire cable being cut.

I have shown my invention as embodied in a cutting tool comprising a cylinder 5 closed at its outer end by a head 6 conveniently formed integral with cylinder 5. The cylinder 5 preferably is provided with a liner 7 fitting tightly therein for the major portion of the length thereof, the inner surface of this liner being accurately machined and polished. The other or inner end of cylinder 5 is closed by a head 8 bolted thereto and seating tightly thereon, this head 8 having an extension 9 fitting into the inner end of liner 7 providing a fluid tight and pressure resistant seal therewith. This tight fit of extension 9 in the liner 7, in conjunction with the accurate seating of head 8 upon the end of cylinder 5, effectively guards against leakage of hydraulic fluid at the inner end of the cylinder. Within the broader aspects of my invention, any suitable known means may be provided to guard against such leakage, though the means shown is sufficient if proper care is exercised in machining and fitting of the parts.

A piston 10 is mounted within cylinder 5 for reciprocation therein. This piston is spaced from the cylinder heads 6 and 8 so as to provide a reservoir chamber 11 at one side of the piston and a pressure chamber 12 at the other side thereof. The piston 10 is provided with pressure resistant sealing means 13 of a suitable known type extending circumferentially thereabout adjacent the pressure chamber side of the piston, effective for preventing leakage of hydraulic fluid under high pressure in chamber 12 about the piston. It will be seen that the cylinder and the piston provide both a reservoir chamber and a pressure chamber, thereby avoiding necessity of providing a hydraulic fluid reservoir chamber exterior of the piston, which is conducive to compactness of construction.

The piston 10 is mounted upon a piston rod 15 slidable through and extending beyond the piston heads 6 and 8. A sectional ring 16 seats in a corresponding groove extending about rod 15 in a corresponding recess in the inner face of piston 10, effective for preventing inward movement of piston 10 relative to rod 15. A washer 17 is disposed about rod 15 and seats on the outer face of piston 10, this washer being confined between the piston and a snap ring 18 engaging in a corresponding circumferential groove in rod 15. It will be clear, from what has been said, that the piston rod 15 is secured to the piston 10 for

3

movement therewith lengthwise of cylinder 5. The piston 10 is provided, adjacent its outer face, with an annular recess extending about rod 15 and receiving an oil seal 19 of suitable known type effective for preventing leakage of hydraulic fluid or oil about rod 15 under the high pressures to which such fluid is subjected in the pressure chamber 12. A second snap ring 21 is mounted in a circumferential groove in piston rod 15, outward thereof beyond ring 18 and serves as a stop, in cooperation with cylinder head 6, for limiting outward travel of piston rod 15. The piston head 6 is provided with a thickened element or boss 22, through which the piston rod 15 is slideable, this boss being provided with annular recesses extending about rod 15 in which are mounted seals 23 and 24 of suitable known type effective for preventing leakage about the piston rod of the hydraulic liquid subjected to high pressure in the pressure chamber 12.

The piston 15 is drilled from its outer end to provide an outer bore 26 opening through the outer end thereof, an intermediate bore 21 of less diameter than bore 26 and opening into the inner end thereof, and an inner bore 28 of less diameter than bore 27 and opening into the inner end thereof, this inner bore 28 terminating a short distance inward beyond the piston 10. The piston rod 15 is further provided with a diametrical bore 29 intersecting bore 28 adjacent the inner end thereof and establishing communication between bore 28 and the reservoir chamber 11 of the cylinder. The outer end of bore 28 is slightly flared to provide a seat for a ball check valve 30, which opens outward away from bore 28 and normally is held seated by a light compression spring 31 disposed in bore 27 and confined between valve 30 and a tubular retainer 32 disposed in bore 27 and secured in position by a screw 33 extending through a wall of rod 15 and threading through the outward extension of retainer 32. The piston rod 15 is further provided with radial port 35 opening into bore 27 a short distance outward beyond the piston 10. The port 35 is controlled by a ball check valve 36 of known type comprising a casing having a reduced neck 37 threaded into a recess in piston rod 15 concentric with port 35. The valve 36 comprises a ball valve member 38 which opens radially outward of the piston rod 15 and normally is held closed by a compression spring 39. This type of check valve is well known and requires no further description. Suffice it to state that the port 35 is controlled by a suitable check valve which closes inward toward the piston rod 15 and opens outward radially thereof, the ball or valve member normally being yieldingly held seated or closed.

The outer end portion of bore 27 has a slight outward flare and is threaded for engagement by a correspondingly formed and threaded element 41 of a pump barrel 42 thus secured in piston 15 coaxially therewith. Pump barrel 42 extends through bore 26 in concentric spaced relation to the surrounding wall of piston rod 15 and projects outward a considerable distance beyond the outer end thereof. The outer end portion of piston rod 15 is reduced slightly in diameter to provide an annular shoulder 43 thereon. An elongated sleeve 44 fits about the reduced outer end portion of piston rod 15 and seats at its inner end on shoulder 43. The outer end of sleeve 44 fits about a reduced neck 45 of the head 46, the neck 45 of which screws onto a head 47 suitably secured, conventionally by welding, on the outer

4

end of pump barrel 42. Head 46 seats against the outer end of sleeve 44 and, in cooperation with shoulder 43, restrains it against endwise movement relative to piston rod 15 and pump barrel 42.

An elongated rod-like pump plunger 50 is mounted in pump barrel 42 for reciprocation therein. This plunger 50 extends outward through head 46, there being suitable known sealing means 51 and 52, carried by head 46, disposed about plunger 50 effective for guarding against leakage of hydraulic fluid or liquid outward thereabout. At its outer end the plunger 50 is secured in the plug 53 which is suitably secured, conveniently by spot welding, in the outer end of the tubular guide member 54 extending inward about sleeve 44 in concentric spaced relation thereto. A collar 55 is secured in the inner end of guide member 54, conveniently by spot welding, and is slideable along the outer end portion of piston rod 15 and along the sleeve 44. The plug member 53 is suitably bored and tapped for reception of a screw stud 57 of a handle 58 secured, by means of stud 57, to plug 53. As will be clear from what has been said, the handle 58 provides means for reciprocating the plug 53, and with it the pump plunger 50 and the guide member 54, the latter, in cooperation with collar 55 and sleeve 44, serving to guide the plunger 50 and guarding against objectionable flexing or bending thereof, conducive to ease and accuracy in operation of the pump.

The pump plunger 50 is of but slight diameter relative to piston 10, as will be clear from Figure 1. On the outstroke of plunger 50, hydraulic liquid, preferably a light oil of suitable type and having a low freezing point, with which the cylinder chambers and communicating passages are filled, is withdrawn from the reservoir chamber 11 through the passage comprising the bores 28 and 27, into the pump barrel 42. During such outstroke or suction stroke of the pump plunger 50, the ball check valve 30 opens in opposition to the compression spring 31, which may be of comparatively light weight, as will be understood. During the in or compression stroke of pump plunger 50, the oil withdrawn from the reservoir 11, is forced into the pressure chamber 12. During that stroke of the pump plunger the ball valve 38 of check valve 36 opens in opposition to the compression spring 39, which also is of comparatively light weight, and upon completion of the compression stroke of the pump plunger the ball valve 38 is seated and held seated by the pressure in the pressure chamber 12, as will be understood. The total pressure exerted on the outer face of the piston 10 incident to the in stroke of pump plunger 50 is much greater than the total pressure applied to the pump plunger, as will be understood. It is desirable, in order to avoid damage to the tool, that means be provided whereby excessively high pressure, such as might cause damage, be guarded against. To that end, I provide a pressure relief valve 60, of suitable known type, mounted in the piston 10. This valve comprises a housing 61, which has a press fit in piston 10, this housing having a passage 62 opening into the pressure chamber 12. The passage 62 is controlled by ball valve 63 yieldingly urged closed by a compression spring 64 mounted in a bore 65 of housing 61, of greater diameter than the passage 62. A tubular spring retainer or collar 66 is secured in the inner end of housing 61. The piston 10 is urged toward the outer end of cylinder 5 by a compression spring 68 disposed about

piston rod 15 and confined between the extension 9 of head 8 and the piston 10. It will be clear that as the piston 10 is forced inward by the pressure applied thereto at its outer face, the spring 68 is placed under increasing compression and presents increasing resistance to inward travel of piston 10. The spring 68 is of adequate strength to assure that the piston 10 will be returned to its outermost position, with the snap ring 21 in contact with head 6, when communication is established between pressure chamber 12 and reservoir 11 for bypassing the hydraulic liquid about the piston 10, as will be explained more fully later. The maximum strength of spring 68 is slight compared to the total pressure applied to the outer face of piston 10 for forcing it inward and does not present any objectionable resistance to such inward movement of the piston. In the event the pressure within the pressure chamber 12 attains an objectionably high value, such as might result in injury to the tool, the pressure release valve 60 opens. That permits escape of the hydraulic liquid from the pressure chamber 12 to the reservoir chamber 11, thereby effectively preventing any further increase in total pressure applied to the outer face of piston 10, even though operation of the pump being continued. Mounting the pressure relief valve 16 with the piston 10 assures that that valve is effectively enclosed and guarded and also eliminates objectionable projections beyond the cylinder 5, such as would result from positioning the pressure relief valve exteriorly of the cylinder.

The wall of cylinder 5 is thickened at one side thereof, at 70, this thickened portion of the cylinder wall extending from the boss 71 formed integral with the thickened portion or boss 22 of head 6. The thickened wall portion 70 of cylinder 5 is drilled to provide a duct 72 which opens through a port 73 in cylinder liner 7 into the reservoir chamber 11. Duct 72 opens, at its outer end, into a duct 74 which opens, at its outer end, into a space 75 in the inner end of boss 71, between the inner end of bore 76 thereof and a flanged closure plug 77 threaded into boss 71. The plug 77 is bored and tapped from its inner end for reception of the threaded enlargement 78 of a valve stem 80 extending through plug 77 and through a stuffing box 79 at the outer end of plug 77. A flanged handle or knob 81 is fixed on the outer end of stem 79. The valve stem 79 is provided, at its inner end, with a stud 82 disposed for contact with a ball valve 83 seating in a recess 84 extending inward from space or chamber 75. The ball valve 83 normally closes the outer end of a short duct 86 opening into the pressure chamber 12 at the outer end thereof. In the use of the tool, ball valve 83 is held seated by stud 82 and, in the operation of the pump, pressure is applied to the piston 10 as above described. Upon completion of the operation performed by the tool, it is desirable that the piston 10 be returned quickly to its outer position so as to condition the tool, without delay, for performing a succeeding operation. That is accomplished by turning the valve stem 79 outward a sufficient distance to permit opening of the ball valve 83. That valve is then opened by the pressure within the chamber 12, due to the outward pressure exerted by compression spring 68 on the piston 10. The piston 10 is quickly moved to its outermost position by spring 68, and the hydraulic liquid displaced from chamber 12 by this outward movement of piston 10 is by-passed about the piston, through the passage provided by the

intersecting ducts and the associated spaces and ports, above described, and enters the reservoir chamber 11 through the port 73. The valve stem 79 is then turned in so that the stud 82 holds the ball valve 83 tightly seated, and the tool is then conditioned for a further operation.

The inner cylinder head 8 carries a work receiving or cutter head 88 integrally connected to head 8 by a neck 89. The head 88 is of approximately U-shape in plan, comprising the two arms 90 and 90a defining between them a substantially U-shaped recess. The head 88, including neck 89 thereof, is suitably bored for reception of the inner end portion of piston rod 15, slidable through head 8. The bore 92 (Figure 2) of head 88 and neck 89 is of greater diameter than bore 93 through head 8, which snugly receives the piston rod 15, providing clearance about rod 15 inward beyond cylinder head 8. Head 88 is further provided, at each side of bore 92, with a lengthwise groove 94 opening into bore 92, these grooves 94 being disposed in the plane of cutter head 88. At the outer end portion of head 88 and neck 89 thereof, the grooves 94 are of increased depth, at 94a, to provide clearance or relief for a cutting blade slidable in the grooves 94.

The grooves 94 slidably receive the side portions of a cutting blade 96 of hard steel. This blade is substantially rectangular in plan and in transverse section, and is of considerable thickness, the side portions thereof being shaped conformably to and slidably mounted in the grooves 94. The inner end portion of blade 96 fits into a slot 97 in the outer end of piston rod 15, extending diametrically thereof. A pin 98 is secured in blade 96, conveniently by being a press fit therethrough, adjacent the inner end thereof. This pin 98 extends through openings 99 in the fingers 100 at the sides of slot 97. The openings 99 are of somewhat greater extent lengthwise of piston rod 15 than the pin 98, providing in effect a pin and slot connection between blade 96 and piston rod 15. The pin 98 is so disposed that in the movement of piston rod 15 outward through head 8 the piston rod at the outer end of slot 97 contacts the inner end of blade 96, for transmitting directly thereto the pressure exerted by the piston rod and the associated piston. The flat inner end of blade 96 seats against the corresponding flat area of the piston rod 15 during outward movement thereof, providing a substantial area of pressure contact therebetween, and fingers 99 of piston rod 15 assist in restraining blade 96 against twisting; as will be clear from what has been said and from Figure 4. That reduces likelihood of breakage, such as might occur if the pressure from the piston rod were transmitted to the cutting blade through the pin 98 or analogous member. When the piston rod is moved inward, after completion of a cutting operation, the fingers 100 thereof pick up the pin 98 and thereby move the blade 96 inward into retracted position with the piston rod 15, as will be understood.

The inner end portion of arm 90 of cutter head 88 is slotted for reception of one end portion of a yoke 102 pivoted therein by a pin 103. The yoke 102, when in its normal closed position, bridges the space between the arms 90 and 90a. The other arm 90a of cutter head 88 is slotted for reception of a latch member 105 pivoted therein on the pin 106. The latch member 105 is urged in latching direction, as viewed in Figure 1, by compression spring 107 confined between thumb piece 108 of member 105 and neck 89,

this spring seating at its ends in suitable recesses bored in the neck and in the thumb piece 108. At its inner end the latch member 105 is provided with a bill 110 which engages over a co-operating extension 112 of yoke 102, for retaining the latter in its closed position. Movement of the latch member 105 in latching direction is limited by a finger 115 thereof disposed to contact the inner end of element 116 of cutter head 88.

The yoke 102 is provided with a recess 118 of approximately semi-circular shape into the sides of which open two grooves 120 corresponding to the grooves 94 of cutter head 88. The grooves 120 are continued through yoke 102 to the inner face thereof and the yoke 102 is slotted from recess 118 to its inner end face, for reception of the cutting blade 96. When yoke 102 is secured in its normal closed position, the grooves 120 thereof are aligned with the grooves 94 of cutter head 88, for reception of the side portions of the blade 96. The latter, blade 96, is suitably formed and ground from one face thereof to provide a slightly concaved or beveled area 121 and, at the inner end of the blade, an approximately semi-circular recess defined by a cutting edge 122. The blade 96 is so disposed, relative to the yoke 102, that the unground or flat face of blade 96 is presented to the flat surface 124 of yoke 102 overlying slot 125 therein (Figure 4) contiguous to the grooves 120. The upper wall of yoke 102, defining the recess 118, is beveled downward and inward at 125, to provide a cutting edge 126 defining the recess 118, in major portion.

In using the tool for cutting a wire cable c (Figure 4), with the piston 16 in its inner retracted position, with the blade 96 correspondingly retracted, the yoke 102 is released and swung to open position and is then closed, and secured closed, with the work piece, such as the cable c, disposed in the recess 118. With the ball valve 83 held tightly seated in the manner previously described, the pump is operated thereby forcing the piston 1, and with it the piston rod 15, outward of cylinder 5 under high pressure. As the piston rod 15 is forced outward it forces the cutting blade 96 outward toward the yoke 102, and the cable c is cut by the cutting edge 122 of blade 96 in cooperation with the cutting edge 126 of the yoke 102.

The pressure of the piston rod 15 is applied thereby directly to the inner end of the blade 96 in direct contact therewith, during the outward travel of piston rod 15, thereby relieving pin 96 of stresses incident to the movement of blade 96 in cutting or outward direction, as above explained. Upon completion of the cutting operation, the valve stem 97 is turned outward an appropriate distance and the compression spring 68 then returns the piston 10, and with it the piston rod 15 and blade 96, to retracted or inner position. The stem 79 is then turned inward so as to hold the ball valve 83 tightly seated and the tool is then conditioned for a second cutting operation. That permits of comparatively quick operation of the tool with a corresponding increase in the number of cutting operations possible in a given time period, breakage or damage of the tool due to excessive pressure during the cutting operation being guarded against by provision of the pressure relief valve 60, in the manner previously described.

It will be understood that changes in detail may be resorted to without departing from the

5 field and scope of my invention, and I intend to include all such variations, as fall within the scope of the appended claims, in this application in which the preferred form only of my invention has been disclosed.

I claim:

1. In a hydraulic cutting tool, a cylinder having a closure head at each end, one of said heads having an extension providing a cutter head, a piston operating in said cylinder, a piston rod movable with said piston slideable through said one head, a cutting blade slideable in said cutter head guided thereby, said blade having an outer end and a flat inner end of substantial area, and lost motion pin and slot operating connections between said rod and blade whereby said rod in its outward travel contacts the inner end of said blade for applying pressure thereto and in its inward travel picks up said blade and returns the latter to its inner position, said rod having a flat surface of substantial area disposed for pressure contact with the inner end of said blade in said outward travel of said rod.

2. In a hydraulic tool, a cylinder having a closure head at each end, one of said heads having an extension providing a work receiving head, a piston operating in said cylinder, a piston rod movable with said piston slideable through said one head, a pressure applying member slideable in said work receiving head guided thereby, said member having a flat inner end of substantial area, and a pin and slot connection between said rod and the inner end portion of said member providing lost motion therebetween whereby said rod in its outward travel contacts the inner end of said member for applying pressure thereto and in its inward travel picks up said member and returns the latter to its inner position, said rod having a flat surface of substantial area disposed for pressure contact with the inner end of said member in said outward travel of said rod.

3. In a hydraulic tool, a cylinder having a closure head at each end, a pressure applying member having an inner portion of rectangular cross section and a flat inner end of substantial area, a piston operating in said cylinder, a piston rod movable with said piston slideable through said one head having in its outer end a transverse rectangular slot providing spaced fingers 50 snugly receiving between them the inner end of said member, said rod having at the inner end of said slot a flat surface of substantial area disposed for pressure contact with the inner end of said member, said fingers having aligned slots 55 therein, and a pin secured through said member extending into the slots of said fingers, the latter slots providing for contact of said rod in its outward travel with the inner end of said member and for picking up of said pin by the fingers of said rod in its inward travel.

WALTER E. NORTHCUTT.
